APPARATUS FOR COKING COAL BRIQUETS.

1,155,486.

Specification of Letters Patent.

Patented Oct. 5, 1915.

Application filed June 19, 1914. Serial No. 846,070.

To all whom it may concern:

Be it known that I, PAUL HEIN, director, a subject of the King of Prussia, and residing at Essen-Rüttenscheid, in the Kingdom of Prussia and German Empire, have invented certain new and useful Improvements in Apparatus for Coking Coal Briquets, of which the following is a specification.

If in the manufacture of coal briquets a water-soluble binding medium or agglutinant such as sulfite lye that is the lye obtained from the sulfite cellulose manufacture and called "cellulid" or "glutrin," molasses and so forth is employed, the briquets formed by compression must be subjected for some time to the action of dry heat for the purpose of carbonizing the agglutinant to render same insoluble, the temperature being kept so high that a coking of the agglutinant takes place, while the coal itself does not begin to coke or disappear.

The coking of the agglutinant is effected in special furnaces or drums, for example in ordinary shaft furnaces with throttled discharge, or in shaft furnaces with superposed drums arranged therein through which the briquets pass in succession in the opposite directions to the ascending hot gases. The lowest drum located in the hot test zone of the furnace exerts the most intense coking effect, but the heat absorbed by the briquets in this drum does not act for a sufficient length of time to produce an adequate or practically complete coking of the binding medium.

The improved operation according to my invention consists in starting with the coking of the agglutinant in a shaft furnace of the said kind and in completing the coking action in a special reservoir or chamber provided for the purpose, whose action is comparable to that of the modern cooking range, at a temperature which drops somewhat below the maximum temperature of the furnace, that is to say without further heating. This final or after-coking reservoir or chamber is in direct communication with the outlet for the briquets from the furnace, for example by the intermediary of a passage closed to the outer air, and which may be located either wholly or in part outside the furnace.

A novel apparatus for carrying my invention into effect is illustrated in conjunction

with a shaft furnace with superposed coking drums in the accompanying drawing.

In the drawing the lower part of the known type of furnace is represented in section together with the lowest coking drum. The hot gases coming from the furnace issue from the passage *a* into the shaft *b* and then upward through the rotating drum *c* and through the other rotating drums arranged above it but not shown. These drums consist of cylindrical boxes having perforated walls so that the hot gases have free access to the briquets contained therein. The outer casing of the drum is stationary and is provided with inlets and outlets. While in the known shaft furnaces of this kind the outlet from the lowest drum is carried outside the furnace and directly to an open conveyer apron upon which the hot briquets are conveyed to the place of storage or to trucks, in my novel arrangement the outlet *d* from the lowest drum communicates through a pipe *e*, or some other closed passage, with another drum *f* rotating in a stationary casing *g* adapted to receive the hot briquets in its eight rotating compartments. The briquets are discharged through a chute *h* in the casing *g* onto a conveyer apron or the like (not shown).

The drum *f* may be arranged wholly or partially outside the shaft furnace and is preferably driven positively by the mechanism driving the drums above referred to. The drum *f* serves a two-fold purpose, that is to say, the final or after-coking of the briquets not yet ready for store and the correlated slow cooling of the superficial strata of the briquets, so that the subsequent cooling can be effected by means of water on the conveyer apron or in the storage place without causing cracking or breaking of the superficial strata as has hitherto been the case. The compartments in drum *f* are of such a size that is to say the capacity of the drum is so great that the latter is able to rotate at a far lower speed than the roasting drums in the shaft furnace without causing blockage of the passage *e*. It is essential to keep the speed of rotation of this after-coking drum *f* so low that the briquets remain for a sufficient length of time in the zone of moderate heat to insure the thorough roasting of the interior of the briquets before they leave the drum *f*.

The drum *f* consists of a long hub 1 keyed to the rotary shaft 2 and provided with radially projecting walls 3 extending longitudinally of said shaft throughout the length 5 of the drum. The radial walls 3 have flanges 4 to which the end walls 5 of the drum are secured by rivets, or the like. The construction of the drum, of course, may be varied to suit different requirements.
10 There is no casing within casing *g*.

What I claim is:

In an apparatus for coking coal-briquets containing an agglutinant capable of carbonization, the combination with a furnace,

of a series of superposed rotatable coking drums, a rotatable after-coking drum, a chute leading from the lowermost of said drums to said after-coking drum, said after-coking drum being partially built and extending into said furnace, and a stationary 15 casing inclosing said after-coking drum and having a discharge opening.

In testimony whereof I have affixed my signature in presence of two witnesses.

PAUL HEIN.
